ASH HANDLING DEVICE

Carl H. Will, Winnetka, and Benjamin F. Monroe, Chicago, Ill., assignors to Tropic-Aire, Incorporated, Chicago, Ill., a corporation of Delaware

Application May 3, 1940, Serial No. 333,106

14 Claims. (Cl. 206—19.5)

This invention relates to improvements in ash receptacles, particularly adapted for the use of smokers and to be placed near or on the seats of passenger vehicles.

Objects of the invention are: to provide a relatively cheap and structurally efficient device and to provide a device in which each of a plurality of ash receptacles can be easily detached for cleaning by boiling. Another object is to provide a device which has a tray emptying into a dumping receptacle, which receptacle can be moved to dumping position and which has latching means so placed that it is not likely to be tampered with by unauthorized persons, such as passengers, who to amuse themselves undertake to discover just how the device is made and how it can be opened.

In an attempt to avoid unauthorized or accidental unlatching and opening of the dump receptacle, the present invention provides an arrangement by which, when the tray is in open position, that is, in receiving position, the latching means is hidden. Only when the tray is moved to a certain predetermined position in dumping direction is said release means made accessible to those who know its position. The device further requires that after the release means is rendered accessible by a certain predetermined amount of motion of the tray in dumping direction, and after release has been accomplished, the tray must again be moved in the same direction to permit completion of the motion of the receptacle to dumping position. After release of the latch the receptacle can start its movement toward dumping position, but cannot complete that movement until a further movement of the tray in the same direction is made to release a second stop provided by means on the walls of the receptacles.

It is further desirable, and may be considered an object, to so place the release means that it is on that side nearest the user when the device is applied, for example, to the outer wall of a vehicle between two seats. To carry out this scheme the devices would be made in rights and lefts and, although this may be advisable in some instances, it is not considered that the invention is limited to this feature.

Another object of the invention is to utilize the dump receptacle as an ornament, so related to the other parts of the receptacle that it extends beyond and covers those parts, and thus the outer margins of said dump receptacle may engage the support to form a neat, substantially jointless fit therewith.

Objects, features and advantages of the inven-

tion will appear in the description of the drawings forming a part of this specification, and in said drawings—

Figure 1 is a front view of the device applied to a support and with the tray in receiving position;

Figure 2 is a vertical section taken approximately on line 2—2 of Figure 1;

Figure 3 is a vertical section on line 3—3 of Figure 1 but with the tray moved sufficiently in dumping direction to permit access to the means which releasably secures the dump receptacle in receiving position;

Figure 4 is a vertical section similar to Figure 3 showing the dump receptacle unlatched and moved part way toward dumping position but held by the tray from complete movement to that position until the tray is additionally moved in the same direction to release the dump receptacle;

Figure 5 is a vertical section showing the receptacle in dumping position;

Figure 6 is a horizontal section on line 6—6 of Figure 2;

Figure 7 is a horizontal section on line 7—7 of Figure 3;

Figure 8 is a horizontal section on line 8—8 of Figure 3; and

Figure 9 is a vertical section showing how the rear wall of the dump receptacle engages the forward edge of the tray when moving to receiving position.

In the drawings, the numeral 1 indicates a support having a recess 2 which receives the inner or base section 4, herein pan-shaped and marginally flanged. Hinged to the base in a manner to be described in detail is an outer or dumping receptacle 5 which acts as an ornamental closure. The hinge is so arranged that the receptacle can swing outwardly and downwardly to the dumping position of Figure 5. This dumping receptacle 5 is herein composed of a front casing section providing a front wall 6 having an opening 7 through which opening ashes can be deposited in a tray 10 having the general form of a segment of a cylinder with closed ends 11.

The ends 11 (see Figure 6) have openings 13 with which are engaged trunnions 12 of resilient arms 14 extending outwardly from the base. The tray 10 is removably held in a manner to be described, and its open side 10^a is opposed to and registers with the opening 7 in the front wall 6 of the receptacle, when both receptacle and tray are in receiving position. A front edge of the cylindrical wall of the tray engages with the

front wall of the receptacle when the parts are in the aforesaid position, and suitable means (to be described) yieldably holds the tray in and automatically moves it to receiving position. It will be seen that the tray when rotated dumps into the receptacle 5.

Manually releasable means is provided for securing the dump receptacle in receiving position and in this instance comprises an arm 15 pivoted as at 16 within the base as shown. A spring 17 yieldably holds a latching shoulder of the arm in latching relation with (see Figure 7) one flange 18 of a pair, which flanges are carried by a rear wall and bottom-forming member 20. The member 6 has two of these flanges 19, one at each opposite margin with which the flanges 18 overlap, and the rear wall and bottom-forming member 20 of the receptacle 5 is detachably secured to these flanges 19 by screws as shown. The arm 15 has a curved bottom surface which cams against the edges of the flanges to raise the latch arm as the receptacle 5 is closed.

The bottom 21 of this member 20 has a forward, upturned portion 22 which lies against the inner side of the front wall 6 of the receptacle. This rear wall and bottom-forming portion 20 lies within or is received by the pan-like base 4 when the dump receptacle is in receiving position, and when in receiving position the rear wall of member 20 engages or substantially engages the rear wall of the pan or base.

It will be noted that one end 11 of the tray acts as means, so related to the releasable means, in this instance arm 15, as to prevent access thereto or sight thereof, until the tray has moved in dumping direction to a predetermined position. The latching device can be viewed, but not easily, only when the tray is moved part of the way towards dumping position, and when this has occurred the finger may be introduced through ash-receiving opening 7 in the front of the receptacle 5.

This arrangement tends to discourage tampering by passengers who are prone, out of curiosity, to finger any device which they can see. By this invention the means for releasing the dump receptacle cannot be seen when the tray is in receiving position, and when the latch is placed on that side nearest the passenger, is not noticeable when the tray is dumped and, moreover, when the tray has been moved in dumping direction to a position at which the latch is accessible, the parts are so arranged that the latch is not easily seen.

As before stated, the ash tray has the form of a segment of a cylinder in which part of the cylindrical wall is removed to provide an open front for the tray, which opening registers with the ash-receiving opening 7 of the receptacle 5.

It will be seen in Figure 4 that after the locking means has been released and after the receptacle has moved part way toward dumping position, a portion of the tray continues to remain in the path of the rear wall of the receptacle so that said receptacle cannot be moved to full dumping position until the tray has moved in dumping direction beyond that predetermined position required to make said releasable means accessible for release.

It is noted that before the attendant or service man attempts to release the latch he may dump the contents of the tray into the receptacle, then let the tray return and then move it again in dumping direction. This is, however, not necessary because the tray is necessarily dumped as

it is moved to that position which permits access to the latch. As before stated, it is necessary to move the tray farther in dumping direction to bring the cylindrical wall of the tray out of the path of the back wall of the receptacle, whereafter the receptacle can be moved to its full dumping position as shown in Figure 5.

Before describing certain details of the construction which are claimed, along with the broader ideas of means, it may be said that, broadly speaking, a device is provided which requires manual release of the dump receptacle for dumping, but in which that release cannot be accomplished until the tray is dumped, that is, the act of dumping gives access. Another feature is that even after release occurs full movement of the receptacle to dumping position cannot take place until the tray is again moved forwardly in the same direction, that is, in dumping direction, after its preliminary movement to give access for release of the latch.

In devices of this kind it is desirable that the ash tray and dumping receptacle be removable for washing or boiling, to get rid of the well-known tarry odors associated with all tobacco-ash receptacles.

To this end the tray is mounted on trunnions as previously described, each of which engages a corresponding opening 13 of a wall 11. The arms are made of spring material and extend outwardly from the base as shown. When either arm 14 is sprung outwardly, its trunnion is released from its opening and the tray can be so manipulated as to remove the opposite trunnion from the corresponding opening in the opposite end of the tray. When two spring arms are used they may be simultaneously sprung to release the trunnions.

A small coil spring 25 (see Figures 2 and 6) is arranged around a support 26 which immovably holds the trunnion 12 of one side and this spring acts to normally hold the tray in receiving position and in proper relation with the ash-receiving opening of the receptacle. A pin 27 with which one end of this spring is engaged also engages the bearing arm 14 to act as a stop to limit rearward movement of the tray.

It may be noted again that the horizontal cross-sectional configuration of the receptacle is such that a portion of it, member 20, enters the pan-shaped base 4, and another portion 6 overlaps the base and extends therebeyond in opposition to the panel or wall 1 in which the base is set. This not only permits the receptacle to be used as an ornamental finishing front, but increases the cubical capacity of the dump receptacle.

The device by which the dump receptacle is made detachable has the following structure: Referring to Figures 3 and 8; from the bottom of the base 4 extend a pair of spaced arms 30, each of which is curved rearwardly and upwardly to provide a terminal bearing portion 31 formed by a substantially U-shaped bend, the bearing being thus open at the top. On the bottom of the dump receptacle is a U-shaped bracket providing a pair of spaced arms 32. Each arm has an opening for receiving a rod 34. It is noted that this bracket is carried by the removable back and bottom-forming part 20 of the receptacle, and is removable with that part. This rod fits in the open-top bearings 31 and a spring 35 carried by the base is so shaped and so acts as to urge the rod toward and hold it in the bearings 31. To disengage the bar, and therefore disconnect the receptacle 5, the receptacle is brought to a hori-

zontal position and then the hinging end is moved upwardly and then the entire receptacle is moved rearwardly or toward the base, whereby the spring 35 is put under greater tension and the bar is released from the bearings. In assembling the device the bar is placed below the bearing and engaged with the spring 35, and then the receptacle (horizontally disposed) is moved rearwardly against the action of the spring until the bar passes rearwardly of the bearings and then the rear end of the receptacle is moved upwardly, still against the action of the spring, and as soon as the rod has risen to the top of the bearings the spring pushes it forwardly and downwardly into the bearings. This simple detachable hinging device is one form of means by which the lower receptacle may be easily detached for cleaning.

Although all details of construction shown in the drawings herein are claimed, yet certain phases of the invention are broader than those details. I believe it broadly new to provide a device in which there are two receptacles, one dumping into the other, and in which one of the receptacles is releasably held and in which a part carried by or forming a wall of the other receptacle (when in receiving position) hides that means or renders it inaccessible except when the latter receptacle is moved to a predetermined position. I also believe it is new to have a first receptacle prevent the full opening movement of the second receptacle to dumping position until the first mentioned receptacle is moved in dumping direction to a predetermined position.

The means for locking one of the receptacles and the means for preventing access to that locking means may be varied. Also the means by which one receptacle prevents full dumping movement of the other until that receptacle has been brought to a predetermined position, is broader than the means herein by which the wall of one receptacle acts as a stop in the path of a wall of the other, until that predetermined movement has been made. However, this detail is also believed to be new.

We claim as our invention:

1. A device of the class described comprising a base section, a dumping receptacle having a front wall, means connecting the receptacle to the base so that the former can move to dumping position, a segmental tubular tray having end walls, and means pivoting the walls on the base so that the tray is movable to dump into the receptacle, means carried by the base for releasably holding the receptacle in receiving position and extending within said dumping receptacle to a point adjacent its front wall and requiring a tool or the finger of the user for release, said dumping receptacle having an opening in its front wall forwardly through which a portion of said tray extends, and outwardly through which the tray projects during its dumping movement, one of the end walls of the tray when the tray is in receiving position being disposed to prevent access to said releasable means until the tray has been moved a substantial distance in dumping direction.

2. A device of the class described having a pan-like liner, a hollow finishing casing attached to the liner to swing downwardly to dumping position and having an opening therein, said casing having a section which forms therewith a receptacle below said opening, a tray of segmental tubular configuration having end walls, means pivoting said end walls to said liner so that said

tray is normally opposed to said opening to receive ashes and adapted when rotated to dump into the receptacle, said tray having a portion extending through said opening to be engaged by the finger of a user to dump the tray, latching means for releasably holding the receptacle in receiving position and disposed laterally of an end wall of the tray and extending forwardly from the liner into the casing to a point near its front wall, and only accessible through said opening to be directly moved by a finger to release the receptacle for dumping, after the tray has been moved in dumping direction.

3. In combination with a support having a recess therein, a pan-like liner within the recess, a hollow finishing casing closing and extending beyond said recess on all sides and having margins engaging the outer surfaces of the support and having a front wall having an opening therein substantially equal to the width of the recess, said casing having secured thereto a section which normally lies within the recess and which forms with the casing a receptacle, means pivoting the casing to the liner to swing downwardly, a tray of segmental tubular configuration having end walls, said tray pivoted to said liner for rotation on a horizontal axis and normally opposed to said opening and adapted when rotated to dump into the receptacle, said tray having a portion extending forwardly through said opening to be engaged by the finger of a user to dump the tray, said tray being adapted to pass outwardly through the opening when dumped and having a part engageable with the finishing casing and receptacle to limit its range of motion in both directions, means pivoting said receptacle to the liner to swing downwardly to dumping position, a spring for moving the tray to and holding the same in receiving position, latching means carried by the liner and releasably holding the receptacle in receiving position and disposed laterally of an end wall of the tray and which must be directly moved by the user to release the receptacle for dumping, the walls of said tray being so disposed in relation to the latching means and to the opening of the front wall that the tray must be moved a predetermined distance in dumping direction to allow access for release of said latching means by the user.

5. A device of the class described comprising a base section, a dumping receptacle, means releasably hinging the receptacle to the base so that the former can swing outwardly and downwardly to dumping position, a segmental tubular tray and means mounting it on the base to be movable to dump into the receptacle, and means releasably mounting the tray, including bearing arms at opposite ends of the tray and extending outwardly from the base section and into the dumping receptacle, at least one of the arms being yieldable in an axial direction to allow removal of the tray.

6. A device of the class described, comprising a base section, a dump receptacle having a front wall having an opening, means connecting the receptacle to the base so that the former can move to dumping position, a tray having ends and means mounting the tray on the base to be movable in the opening, a catch on the base releasably holding the dump receptacle in receiving position and arranged near said front wall and so that when the tray is in receiving position an end wall thereof prevents sight of and access to the catch, said tray being so disposed in relation to the catch and the opening that it must be

moved to a predetermined distance in dumping direction to allow access for release of the catch by means passed through the opening.

6. A device of the class described, comprising a base section, a dump receptacle having a front wall having an opening, means connecting the receptacle to the base so that the former can move to dumping position, a segmental tubular tray having end walls, and means pivoting the end walls on the base to be partly disposed within and movable through the opening as it moves to dumping position, a catch on the base arranged laterally of an end wall of the tray so that when the tray is in receiving position an end wall of the tray prevents sight of and access to the catch, said catch acting to releasably hold the receptacle in receiving position, said tray being so disposed in relation to the catch and the opening that it must be moved a predetermined distance in dumping direction to allow access for release of the catch by passing the finger through the opening, said tray having a portion engageable by a portion of the dumping receptacle to prevent full opening of that receptacle following release of the catch, unless said tray has been moved substantially to full dumping position.

7. In combination with a support having a recess having a hollow base member fitted therein, a dumping receptacle pivoted to the base and having a front wall, said front wall having an opening at its top and being hinged to the base section so that it can swing downwardly to dumping position, a segmental tubular tray and means pivoting it to the base section, so that said tray has a portion passing through the opening and so that said tray is adapted to move within said opening when moved to dump into the receptacle, and latching means pivoted on the base section disposed at a point laterally of the tray and adapted to hold the dumping receptacle in receiving position, said latching means extending forwardly to a point near the front wall of the dumping receptacle and only being engageable for release by the passage of a tool or finger through said opening, after said tray has been partly moved in dumping direction.

8. A device of the class described, comprising a base section, a dumping receptacle, means releasably hinging the receptacle to the base so that the former can be swung to dumping position, a segmental tubular tray having end walls and means pivotally mounting it on the base to rotate about its tubular axis and so that it can dump into the receptacle, a latch pivoted to the base and lying laterally of and near one end of the tray and normally latching the dumping receptacle in receiving position, said dumping receptacle having an opening in its front wall and the forward end of said latch being near said opening and front wall to be accessible by a finger passed through the opening, and said tray when in receiving position preventing access to said latch through said opening, and having a portion extending through said opening and engaging the outer side of the front face of the receptacle, said tray and receptacle having means cooperable to prevent motion of the receptacle to full dumping position after release of the latch until after the tray has again been moved in dumping direction beyond that predetermined position required to make said releasable means accessible.

9. A device of the class described, comprising a hollow base section, a dump receptacle having a front wall which completely closes and extends beyond the base section, means connecting the

receptacle to the base so that the former can move to dumping position, a segmental tubular tray having end walls and means mounting it on the base to rotate on its tubular axis and to dump into the receptacle, and a catch on the base arranged laterally of one end wall of the tray and pivoted to the base and adapted to hold the receptacle in receiving position, the front wall of said receptacle having an opening through which the finger is passed to release the catch, and an end wall of the tray being so disposed as to act to hide and prevent access to the catch until the tray has been moved in dumping direction.

10. A device of the class described, comprising a hollow base section, a dumping receptacle having a one-piece hollow front wall having an opening, a tray comprising a closed-end hollow segment of a cylinder and means mounting the tray on the hollow base to rotate on a horizontal axis which coincides with the axis of the cylinder, said tray having a cylindrical wall portion which projects through the opening of the wall, and said wall having an opening adapted to be opposed to the opening in the front wall, a latch pivoted to said base section and normally engaging a part of said dumping receptacle to hold it in receiving position, said latch being arranged laterally of an end wall of said tray and a part of the cylindrical wall of the tray and said end acting to prevent access for release of said latch when the tray is in initial receiving position, and permitting such access for release by a finger which has passed through said front wall opening, after the tray has been rotated in dumping direction.

11. A device of the class described, comprising a hollow base section, a dumping receptacle having a one-piece hollow front wall, having an opening, a tray comprising a closed end segment of a cylinder and means mounting the tray on the hollow base to rotate on a horizontal axis which coincides with the axis of the cylinder, said tray having a cylindrical wall portion part of which projects through the opening of the wall, a latch pivoted to said base section and releasably holding the receptacle in receiving position, and means journaling said receptacle for quick release, including arms on the base, each having an open bearing and a rod on the receptacle engageable with said bearings, and a spring engageable by said rod before and during engagement by said rod with said bearings and adapted to yieldably, releasably secure said rod within the bearings for rotation therein, and said base having forwardly extending elements, said elements and tray having means pivoting said tray to the elements, said pivoting means being quickly releasable by moving at least one of the elements in a direction axially of the pivoting means.

12. A device of the class described, comprising an open-front casing adapted to be set into a wall, a dumping receptacle having a front wall adapted to close the casing, said front wall having an opening, means pivoting the receptacle to the casing to swing to dumping position, an ash tray having end walls and a tubular wall having an opening initially opposed to the opening of the receptacle, means pivoting the tray to rotate about the axis of its tubular wall in a manner to have the tray dump into the receptacle and to have a portion of said tray extend through said opening, said tray being adapted to move in said opening during dumping, latching means carried by said casing and receptacle, said means being disposed laterally of an end wall of said tray, a part of the tubular wall of said tray and said

end wall acting to prevent access for release of said latch when the tray is in an initial receiving position, and permitting such access through said receptacle opening for release by a tool or by the user's finger, after the tray has been moved in dumping direction.

13. A device of the class described, comprising an open-front casing adapted to be set into a wall, a dumping receptacle having a front wall adapted to close the casing, said front wall having an opening, means pivoting the receptacle to the casing to swing to dumping position, an ash tray having end walls and a tubular wall having an opening normally opposed to the opening of the receptacle, means pivoting the end walls of said tray to the casing in a manner to have the tray dump into the receptacle and to have a portion of said tray extend through said opening, said tray being adapted to move in said opening during dumping, a latch carried by said casing, means on said receptacle releasably engaged by the latch to hold the receptacle in

receiving position, said latch being disposed between an end wall of said tray and a side wall of the casing, the relations of the said end wall to the latch and of the end wall and latch to the opening of the receptacle being such that only when the tray is moved from its initial position in dumping direction can access be had through said receptacle opening by a tool or the user's finger to release the latch.

10 14. A device of the class described, comprising a base and a dump receptacle, hook-shaped means extending from the base, pin means on the receptacle, and resilient means normally urging the pin means toward the bight of the hook means to releasably secure the pin means therein, and an ash tray and bearings on said base journaling it to move from a receiving to a dumping position, at which latter position it delivers into said dump receptacle.
